UNITED STATES PATENT OFFICE

101,243

DESIGN FOR A COMPOSITE CHARACTER SIGN

Louis L. Rustad, Glencoe, Ill., assignor to Telumigraph Company, Minneapolis, Minn., a corporation of Minnesota

Application July 6, 1936, Serial No. 63,679

Term of patent 14 years

To all whom it may concern:

Be it known that I, Louis L. Rustad, a citizen of the United States, residing at Glencoe, in the county of Cook and State of Illinois, have invented a new, original, and ornamental Design for Composite Character Signs, of which the following is a specification, reference being had to the accompanying drawing, forming part thereof.

Fig. 1 is a perspective view of a composite character sign showing my new design;

Fig. 2 is a plan view of said composite character sign; and

Fig. 3 is an edge view of the composite character sign.

I claim:

The ornamental design for a composite character sign as shown.

LOUIS L. RUSTAD.
